D. L. HARRIS.
AIR COOLING SYSTEM FOR GAS ENGINES.
APPLICATION FILED JULY 12, 1920.

Patented Nov. 15, 1921.

FIG. 5

Ms. A. 3

18 INVENTOR
Daniel L. Harris

BY
H. G. Charles

ATTORNEY

UNITED STATES PATENT OFFICE.

DANIEL L. HARRIS, OF WICHITA, KANSAS.

AIR-COOLING SYSTEM FOR GAS-ENGINES.

1,397,047.

Specification of Letters Patent. Patented Nov. 15, 1921.

Application filed July 12, 1920. Serial No. 395,693.

To all whom it may concern:

Be it known that I, DANIEL L. HARRIS, a citizen of the United States, and a resident of Wichita, in the county of Sedgwick and State of Kansas, have invented certain new and useful Improvements in an Air-Cooling System for Gas-Engines, of which the following is a description, referring to the drawings accompanying this specification.

10 The invention relates especially to an apparatus and assemblage of mechanical elements adapted for cooling the engine as employed in motor cars and like vehicles, generally in present practice using a radiator and water in circulation for cooling purposes. It will be understood that while the mechanism as described refers to an accessory for adaptation to use in such engines and the discarding of their present water 15 cooling apparatus and means, that my invention is equally adapted for installation in new engines, properly designed and constructed with a view of making my invention a composite element therewith. The 20 further advantages will be explained more fully in the description of the drawings, in which Figure 1 shows a side elevation of a gas engine such as is commonly employed in motor cars and with my apparatus installed therewith in combination. Fig. 2 is a cross-sectional view taken along the line 2--2 in Fig. 1 and looking in the direction of the arrows, with a part of the fan case broken away to show the fan. Fig. 3 is a fragmentary side elevation of the rearmost portion of the jacket seen in Fig. 1 and within which as in common practice water is adapted to circulate. Fig. 4 represents a vertical sectional view taken through the conductor 25 leading to the inclosed fan case, and showing a side elevation of a portion of the mechanism operating to reduce the size of the air passage under specified conditions. Fig. 5 is a sectional view taken along the line 5--5 in Fig. 4 and looking in the direction of the arrows. Fig. 6 is a vertical sectional view taken along the rear portion of an engine block and jacket of Fig. 1 showing the opposite end of the device as 30 employed with the mechanism illustrated in Figs. 4 and 5 for reducing the air passage. Fig. 7 is a longitudinal view of this mechanism as seen in Fig. 6. Similar numerals of reference indicate corresponding parts 35 throughout the drawings.

Referring to the drawings, 10 represents

the jacket surrounding the cylinders 11 of a well known type of gas engine as employed in motor car manufacture and in which a cooling fluid such as water is 40 adapted to circulate. In water cooled motors, within a frame 12 a honey combed core or similar structure is employed as a radiator and the water by means of a pump or through other principles as employed is 45 forced to circulate through the jacket to absorb the heat developed within the cylinders and then lose the heat through radiation as the water filters through the core in its circulatory movement back again to and 50 through the jacket. It is well understood that a means of cooling the cylinders is necessary for the proper functioning of the engine and in my invention this cooling is secured through a forced flow of indrawn 55 air circulating through the jacket, in lieu of water, where it absorbs the heat as developed in the cylinder walls, the air thence is expelled into the atmosphere, a fresh supply of air being continually admitted for 60 cooling purposes. In my invention the water core is removed from the radiator frame 12 or in new installations entirely eliminated in the design. The front face of the frame 12 as indicated at 13 is preferably of a 65 screen or perforated plate construction to simulate the appearance of present radiator constructions.

A funnel like horn 14, preferably extending inwardly from the rear of the screen 70 13 is provided with a bell like opening at 15 to admit air. This horn 14 connects by means of a flexible coupling 16 to a pipe 17. The pipe 17 leads to the rear of the jacket 75 10 and to which it connects, a port 18 being cut through the jacket wall to register with the bore of the pipe 17 to receive the indrawn air. The pipe 17 preferably forks 80 at 19 and by means of a flanged bolted connection 20 connects to the port through 85 the jacket 10 which in common practice admits the incoming water to the jacket for 90 circulating purposes. In my invention it is deemed preferable to close this port and use the forked connection 19--20 as a support for the pipe 17 though if desired the opening there into the jacket 10 may be 95 left to also receive the indrawn air.

Leading from the jacket 10 at 21 is a pipe 100 which in ordinary practice is employed to conduct water toward the radiator. In my invention, the pipe 21 connects to a conduc-

tor 22 by means of a flexible coupling 16. The conductor 22 opens into an inclosed fan case 23. At 24 is a belt wheel driven by the engine shaft 25. A fan belt 26 leads 5 to the belt wheel 27 on the shaft 28 which carries a fan wheel 29 rotatably mounted within the case 23 and which during engine operation is adapted to revolve in the direction of the arrow; this fan rotation then 10 creates a suction which draws air through the opening 15 and maintains a constant circulation of air through the horn 14, pipe 17, jacket 10 where the air absorbs the heat as generated, thence is drawn outwardly 15 through the pipe 21 and fan case 23 as indicated by the arrows in Fig. 2 and from which it is ejected rearwardly through the orifice 30 in the case 23 as will be readily understood.

20 My invention thus permits all types of water cooled motors to be remodeled into air cooled motors without materially affecting their outward appearance or design and at a minimum expense and eliminates the 25 dead weight of the water and auxiliary mechanisms usually employed and damages incident to winter travel occasioned by freezeups.

In Fig. 2 is illustrated one method of adjusting and securing the case 23 to the radiator frame 12, it being understood that I do not restrict myself to this assemblage. Bracket members 31 pivotally engage with the case 23 and pivotally engage as at 32 35 with side lugs 33 on the walls of the frame 12 in any mechanical manner. A top member 34 on the case 23 coupled as at 35 to a member 36 integral with the frame 12, for instance at the radiator cap 37 permits of 40 adjustment of the fan belt 26 by means of the adjustable coupling 35.

It will be understood that a chain and sprocket wheels may be employed in lieu of the belt 26 and belt wheels 24 and 27 45 when desired.

Under certain conditions, such as in winter weather, it may be desirable to reduce the bore of the conductor 22 so as to reduce the volume of air flowing through the jacket 50 10 and thereby prevent the engine from becoming too cool, it being well understood that a cold engine does not operate as well as when heated to a certain degree.

A lever 38 is pivotally connected at 39 to 55 lugs carried by the outer end of the bore of the conductor 22. This outer end of the lever is bent at 40 to conform to the curve of the conductor at 41 and is enlarged at its extreme end 42 substantially to the form of a disk. Longitudinally extending within the pipe 21 and jacket 10 is shown a steel pipe 43 housed at its rear end through the jacket wall at 44 and capped without same at 45. The front end of the pipe 43 is secured at 46 to the lug members in rear of

the pivoted lever 38. A brass rod 47 is longitudinally disposed within the pipe 43. A bolt 48 housed through the end cap 45 screws into the rod 47. At 49 a washer on the bolt 48 abuts the end of the rod 47 to form a seat 70 for the compression spring 50 also seated against the inner face of the cap 45. The inner end of the rod 47 pivotally engages at 51 with the upper end of the lever 38 as clearly illustrated.

In the assemblage disclosed in Fig. 4 the engine is assumed to be operating and the full air capacity in circulation through the various parts of the assemblage and through the conductor 22. The inclosed brass rod 80 is thus heated and by its expansion has under the spring resistance 45 acted against the pivoted end 51 of the lever 38 so that the disk end 42 has been forced to lie against the wall of the conductor 22 as illustrated. 85 When the engine is cold or when in winter driving the in-drawn air tends to cool the engine to a greater degree than is desirable for operating purposes, the brass rod 47 also cools and thereby contracts and being secured by the bolt 48, this rod contraction operates to draw inwardly on the pivoted end 51 of the lever 38 or so that the disk end 42 is moved as indicated by the dotted line to the dotted position 42* so that it 95 stands across and in the bore of the conductor 22 thereby reducing the size of the air passage through such conductor 22 and limits the amount of air in circulation; this then reduces the tendency to cool the engine 100 to a greater degree than is desirable for operating purposes.

Such modifications may be employed as lie within the scope of the appended claims. Having fully described my invention what 105 I now claim as new and desire to secure by Letters Patent is:

1. An air cooling system for internal combustion motors, including an air inlet device coupled to the jacket system of the 110 motor, an inclosed fan case coupled to the outlet conductor leading from the jacket system and an air exit in said fan case; a fan, motor operable, rotatably mounted in said fan case and arranged to suck cooling 115 air through the air inlet and jacket system; a valve arranged in said outlet conductor and normally open to permit passage of the air from the jacket into the fan case for expulsion; and members, operatively connected with said valve, arranged within said air passage and adapted to contract when cooled to an undesirable degree, which contraction operates to effect a closing valvular movement to limit the air circulation; 120 all for the purposes as specified.

2. In combination, a jacket surrounding the cylinders of a gas engine, an outlet pipe leading therefrom, a conductor flexibly coupled to said pipe, a lever pivotally 125

mounted within said conductor, a pipe arranged within said outlet pipe and outwardly secured by means of a cap engaging externally the wall of said jacket; a brass 5 rod arranged within said pipe and pivotally connecting at one end to a crank portion of said lever, a bolt inwardly secured from said cap to an engagement with said brass rod, a spring bearing between said rod and cap, 10 said brass rod being adapted during engine operation to expand and elongate under certain specified conditions to occasion a move-

ment of said pivoted lever such as to clear the bore of said conductor and under other specified conditions to contract to occasion 15 an opposite movement of said pivoted lever whereby an inner enlarged portion of said lever will be transversely arranged within the bore of said conductor, all for the purposes as specified.

DANIEL L. HARRIS.
